UNITED STATES PATENT OFFICE

SOLOMON H. GOLDBERG, OF CHICAGO, ILLINOIS, ASSIGNOR TO THE HUMP HAIRPIN MANUFACTURING COMPANY, OF CHICAGO, ILLINOIS, A CORPORATION OF WEST VIRGINIA

HAIRPIN

Application filed July 17, 1926. Serial No. 123,116.

This invention relates to an improvement in hairpins designed particularly for use with short or bobbed hair, wherein due to the particular formation of the hairpin, an unusual frictional grip is secured upon the hair with the result of effectively holding the waves or coils of the hair in place, notwithstanding the short length of the hairpin.

As an advantage of the present invention, 10 in addition to effectively securing the hairpin in place, the hairpin is so constructed that it will not flatten the curl or marcel in the hair. The particular hairpin of the present invention comprises a resilient 15 length of material of greater width than thickness bent to provide an open loop and legs, one of which is substantially straight while the other is crimped. The crimps are so arranged as to contact the face of the 20 straight leg at predetermined points.

In the drawing, Fig. 1 is a perspective view illustrating the use of the hairpin.

Fig. 2 is a side elevational view, and Fig. 3 is a top plan view of the hairpin. 25 Referring in detail to the drawings, 1 designates a length of resilient material such as metal of greater width than thickness. This length of resilient material is bent to form the open loop 2, straight leg 3 and crimped 30 leg 4 provided intermediate its length with a number of crimps designated 5.

In manufacturing the hairpin of the present invention, the crimps are so arranged that their bases may or may not contact the 35 face of the straight leg 3. It is preferable however, that a base of one of the crimps such for instance as shown at 6, shall contact the face of the straight leg 3, for the purpose of providing a more effective spring- 40 like gripping engagement between the two legs in order that the hair shall be secure therebetween. The free terminal of the leg 3 extends in a substantially horizontal plane, whereas, the terminal 7 of the crimped leg 4 is upturned at an angle from the plane of 45 the straight leg 3.

The purpose of this is to facilitate the insertion of the hairpin into the hair.

I am aware that heretofore, hairpins have 50 been patented comprising lengths of resilient

material of greater width than thickness, but I believe I am the first to construct a hairpin of this class in which one of the legs is substantially straight, and the other leg of which is crimped relative to the straight leg. 55

I claim as my invention:

1. A hairpin made of spring material having greater width than thickness, comprising two opposed legs, one leg of said hairpin being substantially straight and the other leg of which is crimped intermediate its length, said legs being united by an integral connecting bend, a portion of the crimped leg being so constructed as to contact a portion of the straight leg. 60

2. A hairpin made of spring material comprising two opposed legs, one leg of said hairpin being substantially straight and the other leg of which is crimped intermediate its length, said legs being united by an integral connecting bend, a portion of the crimped leg being so constructed as to contact a portion of the straight leg. 70
